DESIGN FOR A BAG

Edwin H. Scheele, New York, N. Y., assignor to M. Manischewitz Co., Inc., New York, N. Y., a corporation of New York

Application February 15, 1934, Serial No. 50,746

Term of patent 3½ years

To all whom it may concern:

Be it known that I EDWIN H. SCHEELE, a citizen of the United States, of 419 Fourth Avenue, New York, in the county of New York, and State of New York, have invented a new, original, and ornamental Design for Bags, of which the following is a specification, reference being had to the accompanying drawing, forming part hereof.

Fig. 1 is a perspective view of the bag, showing my new design and

Fig. 2 is a rear elevation thereof.

I claim:

The ornamental design for a bag as shown.

EDWIN H. SCHEELE.
